UNITED STATES PATENT OFFICE.

LOUIS MAICHE, OF PARIS, FRANCE.

TELEGRAPHY.

SPECIFICATION forming part of Letters Patent No. 364,271, dated June 7, 1887.

Application filed October 15, 1886. Serial No. 215,299. (No model.) Patented in England July 30, 1886, No. 9,846.

To all whom it may concern:

Be it known that I, LOUIS MAICHE, of the city of Paris, France, have invented new and useful Improvements in Transmitting-Instruments for Submarine and other Long-Distance Telegraph-Lines, (for which I have obtained Letters Patent in England, dated July 30, 1886, No. 9,846,) of which the following is a full, clear, and exact description.

10. This invention relates to an improved transmitting-instrument for submarine and other long-distance telegraph-lines. The transmission of electrical impulses, as is well known, is very much less rapid through subterranean 15 or submarine cables than through overground lines, by reason of and in proportion to the electric static capacity of the cable, or, in other words, its power of condensation, the cause of the retardation in the transmission of signals 20 being due much less to the time necessary to charge the cable, which speedily attains a degree sufficient to actuate the receiving-instruments, than to the time necessary to discharge the cable—that is to say, for its return to the 25 neutral condition. To obviate the difficulty it is usual to make use of a transmitter-key, which, after the passage of each current, puts the cable to earth, so as to get rid of the residual charge of the cable. In lieu of this a 30 band of perforated paper has been caused to pass between two metallic rollers, the current passing from the one to the other through the perforations, whereby more regular currents are emitted than by a hand-worked instrument, there being two series of perforations 35 to each kind of signal, the one series corresponding to the emissions of the charging-current and the other to those of the current in the opposite direction for neutralizing the charge. 40 The message must therefore be prepared beforehand by perforating the band of paper; and it is necessary to transmit the whole message as thus prepared without the power of interruption in case of unintelligibility.
45. This invention consists in a new automatic distributer of the currents necessary for transmission, which permits the retaining of the ordinary mode of sending and receiving with undiminished rapidity, while affording facility 50 for interruption and repetition, as may be required.

The instrument consists of, first, an ordinary double key worked by hand and having no other function than to effect, by means of a local battery, the release of the distributing 55 apparatus; second, a current-distributing apparatus consisting on the one hand of a clock-train actuated either by a spring-barrel or other power, whereby a regular rotary motion is obtained for actuating the distributor 60 proper.

The distributor consists of a train of clock-work having continuous motion, the last shaft of the train being governed by a fly and rotating at a given speed and carrying eccentric 65 or cam-like contact-disks, which are driven from the shaft by friction-gear. The contacts are normally held at rest by detents; but when one of them is released by the action of a local current established by means of an ordinary key used as a manipulator, one of the contacts is allowed to make a single revolution, after which it is again arrested. During the revolution it touches successively two contact-springs, whereby first a working-current 70 is sent through the line and afterward a current for neutralizing the residual charge. The position of the contact-springs is capable of being so regulated as to give the charge and discharge durations proportional to the capacity of the couple and adjustable according to 75 its daily condition.

In order that the invention may be more readily understood, I have represented in the accompanying drawings, by way of example, 85 different views of a transmitting apparatus constructed according to this invention.

Figure 1 shows an elevation, and Fig. 2 a plan, of the apparatus. Fig. 3 is a section taken on line 1 2. Fig. 1 is drawn on an enlarged 90 scale.

In the figures the same letters of reference indicate the same parts.

a is the base, and *b* the plates, in which is mounted the clock-train *c*, provided with a 95 fly, *d*, for imparting a uniform rotary motion to shaft *e*, upon which are keyed two friction-disks, *f f'*, against which two other disks, *i*, loose on the shaft, are pressed by a spring, *h*. The loose disks have eccentric contacts *k k'*, of 100 platinum. The loose disks are each furnished with stop-pins for engagement with correspond-

ing detents, $l l'$, for preventing their rotation by the disks $f f'$. The detents $l l'$ are carried by the armatures of two electro-magnets, $m m'$, whose operation will be described hereinafter. 5 Upon an insulating support, n , are mounted four springs, $o p$ and $o' p'$, connected diagonally by conductors $r s$, as shown in Fig. 3, connecting the supporting-brackets $u t'$ and $u' t$. The brackets $t t'$, supporting the lower ones of 10 each pair of springs, are connected, the one to the right to the positive pole of a battery, of which the negative pole is to earth, and that on the left to the negative pole of another battery, the positive pole of which is to earth. 15 The contacts $k k'$ communicate with the line through the shaft e .

The operation of the apparatus is as follows: By means of a local battery and an ordinary double key a current is sent through the terminal 1 and the terminals 2 or 3 through the one or other electro-magnet m or m' . Suppose the current to be sent through m , the armature-lever l of that magnet is attracted and the loose friction-disk i and corresponding 20 contact, k , released. The disk i is then rotated by frictional contact with the corresponding friction-disk, f , and its contact k , being carried around with it, comes in contact first with the lower spring, o , and then with the upper spring, 25 p . By this action a negative current from the first battery is sent through the line through the wire x , bracket t , spring o , contact k , and shaft e , and after a short interval, when the contact k has quitted spring o and touched 30 spring p , a positive current from the second battery is sent through the line by the wire y , conductor r , bracket u , spring p , contact k , and shaft e . This second current, being in the opposite direction to the first, has for its 35 object to return the line to a neutral condition before the emission of another current for producing the next signal of the message. If the local current is sent through the other electro-magnet, m' , the operation is similar; but the 40 poles of the line-battery are put to line by the contact k' in the inverse direction—that is to say, the line, instead of receiving first a negative current and then a positive current, which neutralizes the charge of the first, receives first a positive current and then a negative 45 current.

In each case the contact, after performing a complete revolution, is again arrested by the corresponding armature-lever, and cannot 50 again rotate without a fresh current being sent through the electro-magnet.

It will be understood that in order to effect the neutralization of the charge in the line by the second current, which follows the signaling 55 or working current, it is necessary that the passage of these two successive currents should take place during predetermined periods, the relative durations of which must be regulated according to the conditions in which the line 60 is placed. In order to permit of this regulation, the springs $o p o' p'$ and their support n may be shifted relatively to the contacts k ,

the support n being for this purpose mounted on a bracket, v , pivoted on a center eccentric to the shaft e , and provided with a toothed segment, w , gearing with a tangent screw, z , by which the springs $o p o' p'$ are adjusted relatively to the contacts $k k'$ in such a manner as to vary the duration of the contact-springs with the eccentrics. The center about which this adjustment is effected is coincident with the center of the eccentric contact $k k'$. 75

I claim—

1. An instrument for automatically transmitting and distributing currents of opposite polarity to telegraph-lines, which consists of a shaft positively and regularly driven, a contact eccentrically and loosely mounted on said shaft, means for throwing said contact into and out of operative connection with said shaft, 80 and two points on opposite sides of the contact which are charged with currents of opposite polarity and against which the contact impinges, substantially as described. 85

2. In an instrument for automatically transmitting and distributing currents of opposite polarity to telegraph-lines, the combination of a shaft positively and regularly driven, a contact loosely mounted on said shaft, means operated by a local battery for throwing said contact into and out of operative connection 90 with the shaft, and two points or springs on opposite sides of the contact, which are charged with currents of opposite polarity and against which the contact alternatively impinges, substantially as described. 95

3. In an instrument for automatically transmitting and distributing currents of opposite polarity to telegraph-lines, the combination of a contact, a motor for rotating said contact, 105 means operated by a local battery for controlling the connection between the contact and motor, two points on opposite sides of contacts which are charged with currents of opposite polarity and with which the contact alternatively impinges, and means for regulating the duration of the imparted current, substantially as described. 110

4. In an instrument for automatically transmitting and distributing currents of opposite 115 polarity to telegraph-lines, the combination of a shaft positively and regularly driven, two contacts loosely mounted on said shaft, means operated by a local battery for throwing the contacts into and out of operative connection 120 with said shaft, and points or springs on opposite sides of each of the contacts, the diagonally-opposite points being charged with currents of a different polarity from the other two and with which the contact impinges, substantially 125 as described.

The foregoing specification of my improvements in transmitting-instruments for submarine and other long-distance telegraph-lines signed by me this 21st day of August, 1886.

LOUIS MAICHE.
